TIGHTENER AND TYING TOOL FOR FORM
TIE WIRES

Irle M. Reid, Spokane, Wash.

Application November 2, 1948, Serial No. 57,983

2 Claims. (Cl. 140—93)

1

As is well known, forms for the molding of concrete and the like, are frequently held together by wires extending thereacross with pairs of such wires being twisted together about frame members of the form to secure opposite sides of the form together. Obviously, in the interest of uniformity in molding, it is highly desirable that the forms be tightly secured together by such wires. Various means have been provided for tightening and/or tying said wires together and it is to an improved means for accomplishing this purpose that the invention to be described hereinafter relates.

Thus, an object of my invention is to provide an improved tool for tightening and tying form tie wires.

A further object is to provide an improved tool of the class described which includes means for tightening the wires in a position for tying and means for tying said tightened wires together.

A further object is to provide an improved tool of the class described, which includes a hollow body, said body being open at both ends, a cross shaft journaled in said body adjacent one end, a cross bar spanning the body adjacent the other end and adapted to be straddled by a pair of tie wires, said shaft including means for releasably engaging said tie wires, means for rotating said shaft to tighten said tie wires, and means for thereafter rotating said body on its axis for twisting or tying said wires together forwardly of said cross bar.

Other objects and advantages reside in certain structural details, combination and arrangement of the several parts of the device, and will be readily apparent to those skilled in the art upon reference to the attached drawing in connection with the following specification, wherein the invention is shown, described and claimed.

In the drawing:

Figure 1 is a plan view of the device according to the invention;

Figure 2 is an elevational view thereof;

Figure 3 is a longitudinal vertical sectional view taken substantially on the plane of the line 3—3 of Figure 1;

Figure 4 is a bottom plan view of the device, parts being broken away;

Figure 5 is a transverse vertical sectional view taken substantially on the plane of the line 5—5 of Figure 3;

Figure 6 is a transverse vertical sectional view taken substantially on the plane of the line 6—6 of Figure 2;

Figure 7 is a longitudinal sectional view on a

2

slightly reduced scale and showing the position of the parts at the completion of the wire tightening operation;

Figure 8 is a view similar to Figure 7 but showing the position of the parts at the completion of the wire tying operation;

Figure 9 is a fragmentary sectional view similar to Figures 7 and 8 but showing the position of the parts when the same are in a wire releasing position.

Referring specifically to the drawings, wherein like reference characters have been used throughout the several views to designate like parts, the device according to the invention comprises a hollow body 10 of any suitable rigid material which may be in the form of a skirt having open front and rear ends defined by front edges 11 and rear edges 12. The front edge 11, as clearly shown in Figures 7 and 8 is adapted to bear upon the form bracing members or whales 13 which in turn bear against the outer surfaces of the side members of the form, not shown. Moreover, as will appear later, the front edge 11 of the body 10 is freely rotatable on the outer surfaces 25 of the whales 13. Likewise, as is customary, a pair of tie wires 14 extend along opposite sides of the whales 13 and are adapted to be introduced into the body 10 through the open front end thereof.

A cross bar 15 spans the body portion 10 adjacent to but rearwardly of the front edge 11 thereof. Opposite ends of the cross bar 15 are freely received in recesses 16 and 17 formed in the inner periphery of the body 10. Any suitable means such as the cotter pin 18 provides a pivot for mounting the cross bar 15 for swinging movement into and out of the body 10 through said open front end thereof. The recess 16 mounts any suitable spring means 19 which is in operative engagement with the cross bar 15 to load the same for pivotal movement in a direction away from the open front end of the body 10. The other recess 17 and the adjacent end of the bar 15 are formed to provide any suitable releasable latch means such as the ball latch 20 for releasably locking the cross bar 15 in an operative position spanning the body 10. The upper wall of the recess 17 provides a shoulder 21 engageable with the upper edge of the bar 15 to limit pivotal movement of the bar in one direction to the operative position. As clearly shown in Figures 7 and 8, the tie wires 14 when entering the body 10 are adapted to straddle the cross bar 15 for a purpose to be apparent later.

Rearwardly of the cross bar 15, the body 10

is formed to provide a pair of aligned journals 22 and 23 for the end portion 24 of a cross shaft 25. The cross shaft 25 is of smaller cross section than the end portion 24 and merges therewith to provide a shoulder 26 the purpose of which will be apparent hereinafter. The shoulder 26 is laterally outwardly directed and is adapted to at times abut an oppositely disposed shoulder 28 defining the merger between the journal 23 and a journal 27 of reduced cross section for the shaft 25. As shown, the shaft end portion 24 spans the body 10 rearwardly of the cross bar 15 and may extend substantially at right angles to the bar 15 although this arrangement is not necessary. The outer free end of the shaft 25 is of non-circular configuration, as at 29, for readily detachably connecting the shaft 25 to any suitable wrench such as the ratchet wrench 30, Figure 7.

The free end portion 24 of the shaft 25 is formed with a diametrically disposed slot 31 which extends longitudinally of the free end portion and opens through the free end thereof. Opposed terminal portions of the slot 31 are formed with opposed grooves 33 for slidably and rotatably receiving a fixed pin 33 disposed axially of the journal 22. The pin 33 may extend from a closed end wall of the journal 22 or, as shown, may extend from a block or plug 34 fixed in an end portion of the journal 22 in any suitable manner as by the cross pin 35. The purpose of the pin 33 is to prevent the side walls of the slot 31 from being squeezed together under the tension of the wires 14 when the same are tightened by being wrapped around the free end portion 24 of the shaft.

The journal 23 is formed in a boss 36 integral with the body 10 and such boss 36 has pivoted therein a latch pin 37 which extends transversely of the boss in partially intersecting relation to the journal 23. The latch pin 37 is formed with an arcuate recess 38 which has a radius corresponding to the radius of the journal 23 and which is adapted at times to lie flush with the wall of the journal 23 so as to provide a continuation thereof and permit lateral sliding of the end portion 24 of the shaft in one direction. However, when the latch pin 37 is given a partial rotation, the pin partially blocks the journal 23 and prevents lateral movement of the shaft 25 in the journal 23. This is accomplished by the engagement of the shoulder 26 with the latch pin 37. Thus, with the parts in the Figure 7 position, the free end of the end portion 24 is rotatable in the journal 22 while the opposite end portion thereof is rotatable in the journal 23. At the same time, the latch pin 37 blocks the journal 23 laterally outwardly of the shoulder 26 and prevents lateral sliding of the shaft 25 whereby the end portion 24 thereof is releasably locked in an operative position spanning the body 10. At this time, the open end of the slot 31 is closed by the pin 33. With the parts so positioned, the free ends of the wires 14 are inserted into the slot 31 and the shaft 25 given one or more rotations whereby to wind the free ends of the wires about the shaft end portion 24 to tighten the wires to a desired degree of tightness. Thereafter, the body 10 is rotated on its own axis whereby the cross bar 15 twists the wires 14 together below or forwardly of the cross bar whereby to tie them together as clearly indicated in Figure 8. This action not only increases the tenseness of the wires but to some extent will withdraw the free ends thereof from

the shaft end portion 24. However, in the event that the wire free ends are not completely withdrawn from the shaft end portion 24, the latch pin 37 may be given a partial rotation so that the arcuate recess 38 thereof lies flush with the wall of the journal 23 at which time the shaft may be moved laterally to the right as viewed in Figures 7 and 8, whereby the shaft end portion 24 is moved to a retracted position shown in Figure 9. This action forcibly withdraws the wires from the shaft end portion 24 by virtue of the engagement of the wires with the end wall 39 of the journal 23. In this connection, it is preferable that the latch pin 37 be maintained normally in the position wherein it partially blocks the journal 23 and retains the shaft end portion 24 against sliding movement. This is accomplished by a spring 40 which is operatively associated with the latch pin 37 whereby to load the same in the journal blocking position. For convenience in operation, the latch pin 37 is preferably provided with a radially directed finger piece 41 which, upon depression, serves to align the recess 38 of the latch pin with the side walls of the journal 23.

After the free ends of the wires 14 have been stripped from the shaft end 14 as aforesaid, they are frequently kinked or otherwise so disposed as to make it difficult to withdraw them from the cross bar 15. For this reason, the cross bar 15 has been shown and described as being pivoted to the body 10. Thus, when the tool is withdrawn from the wires, the kinked wires may cause the front end of the cross bar 15 to be disengaged from the latch 20 whereby the cross bar swings outwardly of the body 10 and is readily withdrawn from between the wires 14. Thereafter, it is a simple matter to re-engage the latch 20 with the front end of the cross bar 15 and the tool is ready for the next pair of wires 14.

While I have shown and described what is now thought to be a preferred embodiment of the invention, it is to be understood that the same is susceptible of other forms and expressions. Consequently, I do not limit myself to the precise structure shown and described hereabove except as hereinafter claimed.

I claim:

1. A tool for tightening and tying tie wires for 50 a form, comprising a hollow rigid body including a free front edge adapted to bear and rotate upon said form, a cross bar spanning said body rearwardly of said front edge and adapted to be straddled by said wires, said cross bar including a tethered end pivoted to said body whereby to mount said cross bar for pivotal movement towards and away from said front edge thereof, spring means operatively engaging said cross bar and loading the same for rearward pivotal movement away from said front edge, means limiting said rearward pivotal movement of said cross bar to an operative position spanning said body, said body and cross bar including interengaging latch means for releasably locking said cross bar in said operative position, a cross shaft including a free end portion slidably journaled in said body for rotation relative thereto and for relative sliding movement transversely of said body to and from an operative position spanning said body and a retracted position substantially clear of said body, said free end portion of said shaft being formed with a slot opening through said free end portion and extending longitudinally thereof, said slot being adapted to receive said wires therein to engage the same, means for rotating said shaft to

tighten said wires, means for sliding said shaft to said retracted position to withdraw said wires from said slot, said body and shaft being formed with interengaging latch means for releasably locking said shaft in said operative position, and means for rotating said tool on the axis of said body whereby said cross bar is operative to twist said wires together between said cross bar and said form.

2. In a tool for tightening and tying tie wires for a form, a hollow rigid skirt including a free front edge for bearing and rotating upon said form, a cross bar spanning said skirt rearwardly of said front edge and positionable between said wires, said cross bar being pivoted at one end 15 thereof to said skirt for limited movement toward and away from said front edge, interengaging latch means provided on said skirt and cross bar for releasably locking the latter in an operative position spanning said skirt, a cross shaft 20 including a free end portion slidably and rotatably journaled in said skirt and mounted for move-

ment transversely of said skirt to and from an operative position spanning the latter, the free end portion of said shaft being formed with a means for engageably receiving said wires therein, and interengaging latch means being formed on said skirt and shaft for releasably locking said shaft in the operative position of the latter.
